UNITED STATES PATENT OFFICE.

HERMOGENES MANUEL, OF CEBU CEBU, PHILIPPINE ISLANDS.

FINGER-PENCIL.

1,391,556.

Specification of Letters Patent. Patented Sept. 20, 1921.

Application filed November 8, 1920. Serial No. 422,650.

To all whom it may concern:

Be it known that I, HERMOGENES MANUEL, a citizen of Philippine Islands, residing at Cebu Cebu, Philippine Islands, have invented new and useful Improvements in Finger-Pencils, of which the following is a specification.

An object of the present invention is the production of a writing implement which can be permanently attached to the forefinger, or another finger of the user, so that the implement will not be mislaid.

A further object is the production of a writing implement which includes a casing that is designed to surround and to be clamped on the finger of the user and which has an extension in the nature of a barrel that receives therein the lead stick, while means is provided for retaining the body of 20 the stick in the barrel and the point thereof at a desired projection outward of the barrel.

Other objects and advantages will present themselves as the nature of the invention is better understood, reference being had to the drawings accompanying this specification and forming a part thereof.

In the drawings:—

Figure 1 is a perspective view illustrating 30 the application of the improvement.

Fig. 2 is an approximately central vertical longitudinal sectional view through the improvement.

Fig. 3 is a transverse sectional view approximately on the line 3—3 of Fig. 1.

As disclosed by the drawings, my improvement contemplates the employment of a casing 1. The casing may be made of any desired material, metal preferred, and is of a 40 shape corresponding with the forefinger of a person.

The casing, from its open end is provided with a substantially V-shaped slit 2, and on the edges of the slit are outstanding ears 3 45 and 4 respectively. These ears are provided with threaded openings through which passes a screw 5. The outer end of the cas-

ing is tapered or pointed, as at 6, and in the said tapered end there is centrally arranged a barrel 7. The barrel, at determined intervals is provided with openings, as is the tapered portion 6 of the casing. These last mentioned openings are threaded, and receive therethrough threaded elements, such as screws or bolts 8. In the casing and at 50 the inner end of the barrel 7 there is an abutment plate 9 against which the top end of the user's finger contacts. In the barrel there is a marking element such as a stick of lead 10. The screws 8 are adjusted to 55 bind against the marking element 10 so as to hold the point thereof at a desired position outward of the barrel.

It is thought that the foregoing description, when taken in connection with the 60 drawings, will fully set forth the construction, simplicity and advantages of the device without further detailed description.

Having thus described the invention, what I claim, is:—

1. A finger pencil including a casing having a slit side at one of its ends and its opposite end tapered, clamping means between the edges provided by the slit, a barrel in the opposite end of the casing, an abutment 70 between the barrel and casing, said barrel designed to receive therein a writing stick, and adjustable means for retaining the stick in the barrel.

2. In a finger pencil, a casing having one 80 of its ends tapered and its opposite end provided with a substantially V-shaped slit entering one side thereof, offset elements on the edges of the slit, binding means between said elements, an abutment wall in the casing, a barrel extending therefrom and communicating with the open tapered end of the casing, spaced adjustable screws between the tapered end of the casing and the bore of the barrel, and a writing stick in and projecting 85 outward of the barrel and contacted by the screws.

In testimony whereof I affix my signature.
HERMOGENES MANUEL.
